Filed Apr. 3, 1961, Ser. No. 64,586

Term of patent 14 years

(Cl. D34—5)

FIG. 1.

FIG. 2.

FIG. 3.

FIG. 4.

*FIG. 5.*FIGURE 1 is an elevational view of a bar bell, the dominant feature of my design residing in the configuration of each of the nested weights shown in full lines;

FIG. 2 is an enlarged plan view of a bar bell incorporating my new design;

FIG. 3 is a side elevation of the bar bell shown in FIG. 2;

FIG. 4 is a sectional view, taken along the plane indicated by line 4—4 of FIG. 2; and

FIG. 5 is a developed sectional view, taken along the surface corresponding to line 5—5 of FIG. 2.

The bar in phantom lines in FIG. 1 is shown for illustrative purposes only.

I claim:

The ornamental design for bar bell or similar article, substantially as shown and described.
